Primary Examiner — Wan Laymon

(57) **CLAIM**

The ornamental design for a dental instrument, as shown and described.

DESCRIPTION

FIG. 1 is a perspective view of a dental instrument showing the new design for a dental instrument.

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom plan view thereof.

The broken line shown in the figures is for the purpose of illustrating portions of the dental instrument and forms no part of the claimed design.
